UNITED STATES PATENT OFFICE.

OSKAR WIESNER, OF FORST-LAUSITZ, GERMANY.

APPARATUS FOR WITHDRAWING FIBERS, MORE PARTICULARLY HORSEHAIRS, FROM A BUNDLE.

1,178,367.

Specification of Letters Patent.

Patented Apr. 4, 1916.

Application filed July 9, 1914. Serial No. 849,988.

To all whom it may concern:

Be it known that I, OSKAR WIESNER, a subject of the German Emperor, and resident of Mittelstrasse 2, Forst-Lausitz, Germany, have invented new and useful Improvements in or Relating to Apparatus for Withdrawing Fibers, More Particularly Horsehairs, from a Bundle, of which the following is a specification.

10 This invention relates to a device which, on being introduced in a stationary bundle of horse-hair or fibers, always seizes a certain number of hairs and partly withdraws them from the bundle.

15 In known devices for withdrawing single horse-hairs, a pair of pincers, sometimes with an adjustable jaw, is intermittently introduced into the bundle of fibers and withdraws a number of fibers, mostly two or 20 three. In such a case it may happen that the gripper device does not seize any hairs, when it engages with a gap produced by the removal of hairs during the preceding operation, and not yet filled with new hairs.

25 This drawback is avoided according to this invention, by the gripper device first seizing a larger number of fibers than desired, and only separating therefrom the desired number and withdrawing only the latter, while

30 the rest remains in the bundle. To that end, the gripper device is given the shape of a scythe which is introduced into the bundle of hairs to a small depth and takes up a whole layer of fibers. A clamping lever is 35 then moved in the gripper device, which clamps two or three hairs which happen to be exactly in the angle of the scytheslike gripper. The gripper is then withdrawn from the bundle of fibers, and removes only 40 the fibers clamped.

A construction according to this invention is illustrated in the accompanying drawing, in which—

Figure 1 shows a side elevation, Fig. 45 2 a plan, without the bundle of fibers, while Fig. 3 shows the scythe-like gripper on an enlarged scale, and Fig. 4 is 50 a detail view showing the engagement of the drum carrying the reed entering the bundle of fibers and the grooved cam.

As will be seen from Fig. 1, the new device chiefly consists of a grooved cam *a* and of a gripper arm *c* pivoted to swing vertically and laterally about a double joint *b*. The 55 gripper arm *c* carries a downwardly pro-

jecting arm 1 having a pin 2 engaging in the cam groove *a*^o, whereby a vertically reciprocating motion is imparted to the gripper arm *c*.

When the grooved cam *a* is rotated in the direction of the arrow *d* (Fig. 2), the gripper arm *c* is moved laterally by means of a pin *e* eccentrically mounted in the grooved cam, and engaging in the slot *f* in the gripper arm *c*. The gripper passes into the bundle of hairs *g* and takes up, by means of the scythe-like hook *h*, the adjacent layers of hairs. Owing to continued rotation of the grooved cam, the spring-controlled clamping lever *k* pivoted on the gripper arm *c* swings 70 to the left as in Figs. 1 and 2, causing the spring *k*' (Fig. 3) to strike the stop *l*, and a portion of the hairs taken up by the scythe-like hook *h*, is thus clamped, moved downward with the gripper during the further 75 rotation of the grooved cam, and in that way is partly withdrawn from the bundle. Simultaneously with the passage of the gripper through the bundle *g*, a reed *m* enters the bundle below the gripper, in order to 80 prevent the gripper shifting the hairs laterally, and to guide them correctly into the hopper *q* of the spinning spindle *p*. The movement of the reed *m* is brought about by the cam groove *n* on the grooved cam. 85 The reed *m* is carried by a bar 3 which is slotted as at 4, to receive the pin 5 surrounded by the coil spring 6, which tends to lift the reed but permits its yielding downward. The inner end of the bar 3 is held 90 in engagement with the cam groove *n* on the cam block *a*, by the spring *r*. After the gripper arm *c* has reached the end of its movement, the reed leaves the hairs, and at the same time the clamping lever *k* is 95 released owing to the stop *l* ending at *o*, see Fig. 1. The hairs which have reached the hopper *q* of the spinning spindle *p* are spun together there with a guide thread uniformly guided through the spindle *p*, and 100 thus completely withdrawn from the bundle of hairs.

I claim as my invention:

1. An apparatus of the character described comprising a pivoted gripper arm 105 adapted to swing vertically and horizontally through predetermined angles, a blade secured at the end of said gripper arm and spaced slightly therefrom, a clamping lever pivoted to said gripper arm and adapted to 110

- swing into engagement with a portion only of said blade during the lateral movement of said gripper arm, with means for swinging said gripper arm laterally and vertically through predetermined angles about its pivot, substantially as described.
2. An apparatus of the character described comprising a pivoted gripper arm adapted to swing vertically and horizontally through predetermined angles, a blade secured at the end of said gripper arm and spaced slightly therefrom, a bell crank clamping lever pivoted to said gripper arm and adapted to swing into engagement with a portion only of said blade during the lateral movement of said gripper arm, a spring normally throwing said clamping lever out of engagement, with means for swinging said gripper arm laterally and vertically through predetermined angles about its pivot, substantially as described.
3. An apparatus of the character described comprising a pivoted gripper arm adapted to swing vertically and horizontally through predetermined angles, a blade secured at the end of said gripper arm and spaced slightly therefrom, a clamping lever pivoted to said gripper arm and adapted to swing into engagement with a portion only of said blade during the lateral movement of said gripper arm, a grooved rotary cam provided with an eccentric pin engaging said gripper arm, and the said gripper arm being provided with a downwardly projecting arm having a pin engaging in said cam groove, whereby the rotation of said cam imparts to said gripper arm the lateral swinging movement and also a vertical movement about its pivot, substantially as described.
4. An apparatus of the character described comprising a pivoted gripper arm adapted to swing vertically and horizontally through predetermined angles, a blade secured at the end of said gripper arm and spaced slightly therefrom, a bell crank clamping lever pivoted to said gripper arm and adapted to swing into engagement with a portion only of said blade during the lateral movement of said gripper arm, a spring normally throwing said clamping lever out of engagement, a grooved rotary cam provided with an eccentric pin engaging said gripper arm and the said gripper arm being provided with a downwardly projecting arm having a pin engaging in said cam groove, whereby the rotation of said cam imparts to said gripper arm the lateral swinging movement and also a vertical movement about its pivot, substantially as described.
5. An apparatus of the character described comprising a pivoted gripper arm adapted to swing vertically and horizontally through predetermined angles, a blade secured at the end of said gripper arm and spaced slightly therefrom, a clamping lever pivoted to said

gripper arm and adapted to swing into engagement with a portion only of said blade during the lateral movement of said gripper arm, means for swinging said gripper arm laterally and vertically through predetermined angles about its pivot, with a reciprocating reed adapted to project into and to be withdrawn from the bundle of hairs and guide the same while acted on by said gripper arm, substantially as described.

6. An apparatus of the character described comprising a pivoted gripper arm adapted to swing vertically and horizontally through predetermined angles, a blade secured at the end of said gripper arm and spaced slightly therefrom, a bell crank clamping lever pivoted to said gripper arm and adapted to swing into engagement with a portion only of said blade during the lateral movement of said gripper arm; a spring normally throwing said clamping lever out of engagement, means for swinging said gripper arm laterally and vertically through predetermined angles about its pivot, with a reciprocating reed adapted to project into and to be withdrawn from the bundle of hairs and guide the same while acted on by said gripper arm, substantially as described.

7. An apparatus of the character described comprising a pivoted gripper arm adapted to swing vertically and horizontally through predetermined angles, a blade secured at the end of said gripper arm and spaced slightly therefrom, a clamping lever pivoted to said gripper arm and adapted to swing into engagement with a portion only of said blade during the lateral movement of said gripper arm, a grooved rotary cam provided with an eccentric pin engaging said gripper arm, and the said gripper arm being provided with a downwardly projecting arm having a pin engaging in said cam groove, whereby the rotation of said cam imparts to said gripper arm the lateral swinging movement and also a vertical movement about its pivot, with a reciprocating reed adapted to project into and to be withdrawn from the bundle of hairs and guide the same while held by said clamping lever, substantially as described.

8. An apparatus of the character described comprising a pivoted gripper arm adapted to swing vertically and horizontally through predetermined angles, a blade secured at the end of said gripper arm and spaced slightly therefrom, a bell crank clamping lever pivoted to said gripper arm and adapted to swing into engagement with a portion only of said blade during the lateral movement of said gripper arm, a spring normally throwing said clamping lever out of engagement, a grooved rotary cam provided with an eccentric pin engaging said gripper arm and the said gripper arm being provided with a downwardly projecting arm having a pin engaging in said cam groove, whereby the

rotation of said cam imparts to said gripper arm the lateral swinging movement and also a vertical movement about its pivot, with a reciprocating reed adapted to project into 5 and to be withdrawn from the bundle of hairs and guide the same while held by said clamping lever, substantially as described.

In testimony, that I claim the foregoing as

my invention, I have signed my name in presence of two witnesses, this twenty-fifth 10 day of June, 1914.

OSKAR WIESNER.
